AIR BRAKE

Clarence Raymond Jerome, Watertown, N. Y.,
assignor to The New York Air Brake Company,
a corporation of New Jersey

Application June 8, 1942, Serial No. 446,222

2 Claims. (Cl. 303—88)

This invention relates to air brakes and particularly to means for draining water from the main reservoir. Compressed air flowing to the reservoir is cooled in passing through the radiator pipe, and further cooled in the reservoir, with the result that the main portion of its vapor content condenses. Thus accumulation of moisture is particularly rapid while the compressor runs, though it continues at a diminishing rate after the compressor is stopped by the governor.

The present invention provides a valve of desirably simple construction, in which the valve actuating motor is well protected, and in which the water during the period of rapid accumulation is drained away and collected in a chamber external to the reservoir so that entrainment and consequent flow of water to the brake pipe are guarded against. Simple heating means for the water collecting chamber are provided for winter use. The chamber is isolated from the reservoir and drained when the compressor stops. The operation of the valve is controlled by the governor.

The preferred embodiment of the invention is illustrated in the accompanying drawing in which:

Fig. 1 is a vertical axial section of the drain valve in the position assumed when the compressor runs.

Fig. 2 is a similar view showing the position assumed when the governor stops the compressor.

Fig. 3 is an elevation showing the connections.

The valve housing comprises three main parts, a body 6, a cap 7, and a bottom closure 8. The cap 7 has a union connection 9 with the drain pipe 11 leading from the main reservoir 12. A pendant ported flange 13 on the cap enters the drain chamber 14 in the body 6 and assists in confining the annular sealing gasket 15. Machine screws are used to connect the cap and body, as shown.

The flange 13 serves to guide the spherical valve head 16 in motion between the upper seat 17 formed in cap 7 and lower seat 18 formed in body 6. The valve 16 has a tubular stem 19 which extends through aligned openings in body 6 and bottom closure 8 and ports 21 lead to the bore of the stem from the annular chamber 22 formed in body 6 beneath valve seat 18.

When the valve is in its lower position, Fig. 1, water drains from the reservoir 12 past seat 17 to chamber 14 and is arrested at seat 18. When the valve closes upward against seat 17, water collected in chamber 14 drains past seat 18 to

chamber 22 and thence through ports 21 and tubular stem 19.

A jacket chamber 23 in body 6 is supplied with steam through pipe 24 under the control of steam valve 25 and keeps the body above freezing temperature in winter. A drain port 26 disposes of the condensate.

The lower end of body 6 houses a recess 27 surrounded by a recessed flange 28. The bottom closure 8 houses a chamber 29 surrounded by a flange 31. Seated in the recess of flange 28, and clamped by flange 31 is the margin of a flexible motor diaphragm 32. Machine screws connect the flanges, as shown.

15 Threaded on stem 19 above the diaphragm is thrust disc 33. Below the diaphragm is a beaded washer 34, held by nut 35 also threaded on stem 19. This construction seals the diaphragm to the stem 19 and affords limited vertical adjustment of the stem 19 relatively to the diaphragm.

20 At the top of chamber 27 a packing ring 36 encircles the stem and is received in a gland formed in body 6. A follower 31 compresses the packing ring under the urge of the relatively 25 heavy diaphragm loading spring 38 which reacts between disc 33 and follower 31. The spring biases diaphragm 32 downward and at the same time renders ring 36 effective to prevent leakage of water from chamber 22 to chamber 27. A vent 39 disposes of any leakage which may occur.

25 A packing ring 41 seals stem 19 where it passes through bottom closure 8. There is a follower 42 and a relatively light spring 43 which reacts between the follower 42 and nut 35. Spring 38 is the dominant one so that diaphragm 32 and valve 16 have a definite downward bias.

30 Pipe 44 connects chamber 29 with motor chamber 45 of governor 46. To stop the compressor (not shown) governor 46 puts chamber 45 under pressure. At such time the diaphragm 32 will be forced up (Fig. 2). The effect is to isolate chamber 14 from the main reservoir 12, and drain the chamber. The water, and oil if present, pass through stem 19 and do not come into contact 35 with the diaphragm. When the governor starts the compressor, the parts shift to the position of Fig. 1, closing the outlet from chamber 14 and connecting that chamber with the main reservoir.

35 The parts of the device are of simple form and hence inexpensive to construct and maintain.

I claim:

1. In a pressure actuated drain valve for removing water from the reservoir of compressed air systems, the combination of a housing en-

closing a water collecting chamber; a double beat valve, shiftable to connect said chamber selectively with the bottom of the reservoir and with the atmosphere, and including a tubular stem extending through and beyond said housing and serving as the discharge passage from said chamber; a flexible diaphragm connected with said stem, sustained at its margin by said housing, and forming with said housing a single acting pressure motor for shifting said valve; packings sealing between said stem and the housing above and below said diaphragm; and spring means biasing said diaphragm in opposition to said single acting pressure motor.

2. In a pressure actuated drain valve for removing water from the reservoirs of compressed air systems, the combination of a housing enclosing a water collecting chamber with entrance and exit valve seats; a valve comprising a generally spherical head with a depending tubular

stem by which it is guided in the housing and by means of which it may be shifted between said valve seats alternatively to connect said chamber with the reservoir or with atmosphere by way of said tubular stem; a movable abutment connected with and encircling said stem and forming with a portion of said housing an upper working space vented to atmosphere and a lower working space to which pressure fluid may be admitted to force the valve upward, said stem extending to atmosphere through both said working spaces; packing means sealing with said stem to isolate the upper working space from said chamber and the lower working space from atmosphere; and initially stressed springs reacting between each packing means and the abutment to exert sealing pressure on the packing means, the springs being of unequal strength whereby the valve is biased downward.
